UNITED STATES PATENT OFFICE

2,023,874

RAILWAY CAR DOOR TRACK

Floyd V. De Haven, Chicago, Ill., assignor to
Chicago Railway Equipment Company, Chi-
cago, Ill., a corporation of Illinois

Application May 19, 1930, Serial No. 453,695

5 Claims. (Cl. 16—96)

My invention relates to railway car doors and particularly to doors of the type mounted on roller or ball bearings such as are in general use at the sides of box cars. In my copending application Serial No. 453,693 filed of even date herewith, I describe and claim a car door structure having a framing member mounted on the outer face of the door and forming a suitable track-way for an anti-friction supporting element.

10 The general objects of my present invention are the same as of the above-mentioned application, namely, to provide a framing device extending from end to end of the door and forming a suitable track-way for riding on the anti-friction element which supports the door and also to protect the anti-friction element and its carrier track from weather and dirt and injury from external sources.

15 A further object of my present invention is to provide a single structural member forming a framing element for the bottom of the door and adapted to reinforce the same from end to end and also to provide spaced track-ways for riding on an anti-friction element located in vertical alignment with the door. In my above-mentioned copending application the track-ways are located at one side of the door body.

20 In another copending application Serial No. 453,694 filed of even date herewith, I illustrate other forms of door reinforcing and track-way forming structure in some of which the track-ways are arranged in substantially vertical alignment with the door body but in this disclosure the track-ways are formed by cooperating structural members which are formed separately.

25 Another object of my present invention is to provide a single structural member which will have an upwardly facing recess to receive the lower portion of the door and will have a downwardly facing recess forming the track-ways for the anti-friction element.

30 Another object of my invention is to provide a complete device of the type referred to which will comprise a central member secured to the door body and forming the track-ways and side members also applied to the door body and extending below the central member and forming a housing for receiving the anti-friction element and its carrier track.

35 These and other detailed objects of my invention are attained by the structures illustrated in the accompanying drawing, in which

40 Figure 1 is a partial side view of a railway box car having a side door structure embodying my invention.

Figure 2 is a vertical transverse section taken on line 2—2 of Figure 1 and Figures 3 to 8, inclusive, are similar sections illustrating different modifications of my invention.

45 The car side wall 1 may be of any desired construction having an ordinary door opening 2. The door 3 may be of any desired construction, wood or steel, and braced as desired. As illustrated, it is reinforced by vertical front and rear edge members 4 and 5 which cooperate with my lower edging and framing device to provide a rigid door.

50 Inserted between the spaced lower edges of panel 3 and secured to end members 4 and 5 is a structural member 6, the lower portion of which 15 diverges and forms a pair of spaced track-ways 7 for riding upon a ball-bearing 8 which, in turn, is carried on a track 9 formed by the horizontal leg of angle 10. Side members 11 and 12 are secured to the lower portion of the door, preferably by the same rivet 13 which secures the central member 6. Each of these side members is substantially Z shaped in section and their webs are inclined, respectively, outwardly and inwardly from the door whereby their lower flanges 14 20 are spaced a substantial distance apart so as to receive between them the ball-bearing and its carrier track. The webs of members 11 and 12 25 abut the diverging legs of member 6 so that these members mutually reinforce each other particularly against vertical strains. The lower portions of the flanges 14 are adapted to engage the side of the track to hold the remainder of the structure in alignment therewith.

55 By providing track-ways 7 so that they engage smaller bearing circles on the ball-bearing than the bearing circle engaged by carrier track 9, the movement of the door is so proportioned to the movement of the ball that when the door is closed from the position shown in Figure 1 the ball 40 nearest the front end of the door will remain in front of the middle of the door. This will avoid teetering of the door during travel of the car. Similarly, the door will reach its closed position before the rear end of the cage for the rear ball 45 engages the ball and this avoids the necessity of any part of the structure sliding over the ball instead of maintaining a rolling contact therewith.

60 In Figure 3 the Z side members 15 and 16 have substantially horizontal webs and the central member 17 has substantially horizontal shoulders 18 abutting the webs of the side members and this arrangement, together with the securing means 19, tends to form a more rigid framing 55

unit. Also, this modification illustrates the adaptation of my invention for a roller bearing 20 instead of the ball-bearing shown in the other illustrations.

5 In Figure 4 I illustrate my invention applied to a wooden door, the central framing member 21 comprising a U-shape receiving the lower plank 22 of the door and having a downwardly facing V-shape depression 23 forming spaced track-ways 24 for the ball-bearing 25. The side members 26 and 27 are here shown as flat bars or plates extending downwardly from the sides of member 21 and cooperating therewith to form the housing for the ball-bearing, its cage 28 and its carrier track 29.

10 In Figure 5 I illustrate a similar construction in which the central member 30 has a horizontal bottom 31 to the U section and has spaced track-ways 32 projecting downwardly therefrom.

15 Figure 6 illustrates a modification of my invention in which the track-way forming member 33 is secured to one side of a wooden door body 34 but extends under the same with a double crimp providing the track-ways 35 below and in vertical alinement with the door body. The member 33 terminates in a downwardly disposed flange 36 which forms one side of a housing for receiving the ball-bearing 37, its cage 38 and its carrier track 39. The opposite side of the housing is formed by a substantially flat plate or bar 40 secured to the same side of the door as the upper flange of member 33. The device constitutes a reinforcement for the door and, at the same time, the engagement between the downwardly facing edge 41 of the door and the corrugation 42 in the reinforcing member 33 tends to hold the track-ways rigid.

20 In Figure 7 I illustrate a very similar structure in which the main reinforcing member 44 presents a downwardly facing V-like portion in which the track-ways 43 are flat.

25 In Figure 8 I illustrate a similar structure in which the reinforcing member is formed of a single T bar shape, the leg of which is deformed to provide the relatively inclined track-ways 45 for the ball 46 and also to form a depending portion 47 at one side of the track and cooperating with the remainder of the leg and arm 48 of the T, on the other side of the track, to form the housing for the ball and track.

30 In all the forms of my invention illustrated in this application, a single bar forms spaced track-ways in substantial vertical alinement with the car door and beneath the same. One or more additional members cooperate with the track-way forming member to complete the housing for receiving the bearing element and its carrier track.

35 While I prefer to apply the framing and track-way forming device directly to the lower portion of the door body, it is within the scope of my invention to apply the framing device to a separate member forming an extension of the door body. I contemplate the exclusive use of this and other modifications of my invention which come within the scope of my claims.

40 I claim:

1. In a railway car door, a door panel mem-

ber having spaced lower edges, a pair of door framing members having their upper portions applied respectively to the opposite sides of said edges and having downwardly facing shoulders below said portions, a third framing member with a part inserted between said spaced edges and having upwardly facing shoulders seated against said downwardly facing shoulders and constituting spaced trackways for riding on an anti-friction supporting element, and means securing all of said framing members to said panel whereby all of said members mutually reinforce each other.

5 2. In a railway car door, a vertical panel, a pair of separate plate parts overlapping said panel, said parts having downwardly facing offsets, a third part of inverted Y-section also overlapping said panel, the legs of said third part seating against said offsets whereby all of said parts mutually brace each other, and means securing said panel and parts together.

3. A rigid sliding door structure for a railway car comprising a door body panel, an inverted Y-section part, and plate parts on each side of said Y-section part, all of said parts being secured 25 to the door body panel and said plate parts having shoulders seating against the legs of said Y-section part and having portions depending substantially beneath said legs for housing the anti-friction device and its track and guiding the door 30 movements, the shouldered engagement of said parts enabling the same to mutually brace each other against vertical deflection.

4. In a railway car door, a door body member and a door framing device comprising a structural element vertically overlapping and directly secured to the lower portion of said body member substantially from end to end thereof and extending below said body member and provided with integral trackways spaced on opposite sides of the central plane of the door, said device also comprising a pair of Z-bars extending continuously from front to rear of the door and each having an upper flange disposed vertically and overlapping the opposite sides of said body member, the webs of said Z-bars extending away from said body member in opposite directions and the other flanges of said Z-bars extending downwardly at opposite sides of said trackways to form a housing for receiving an anti-friction 50 supporting element and its track, and means securing said element and said Z-bar upper flanges to each other and to said body member to form a rigid unit.

5. In a railway car door having a body panel 55 member, a device extending substantially from the front edge to the rear edge of the door and being of inverted Y shape cross section, the leg and each arm thereof each comprising a single solid flange, the leg of said device overlying said 60 body panel member throughout its length and being secured directly thereto, and the arms of said device terminating in spaced trackways located beneath said leg and on opposite sides of the plane of said leg for engaging spaced bearing 65 circles on an anti-friction supporting element.

FLOYD V. DE HAVEN.
